UNITED STATES PATENT OFFICE.

WEBSTER C. ESTES, OF BROOKLYN, NEW YORK.

DESIGN FOR A WOODEN VIAL-BOX.

SPECIFICATION forming part of Design No. 26,674, dated February 23, 1897.

Application filed January 7, 1897. Serial No. 618,414. Term of patent 14 years.

To all whom it may concern:

Be it known that I, WEBSTER C. ESTES, a citizen of the United States, residing at Brooklyn, in the county of Kings and State of New York, have invented and produced a new and original Design for a Wooden Vial-Box, of which the following is a specification, reference being had to the accompanying drawings, in which—

10 Figure 1 is an elevation; Fig. 2, a plan, and Fig. 3 a vertical section with the cover elevated and showing the vial in dotted lines.

The general configuration of the box is round, and the leading features of my design 15 consist in the long slender cylindrical configuration with plain parallel sides, flat top and bottom, and annular beaded ends.

The design of the cover A comprises the plain parallel sides a a , the flat top b , the an-

nular bead c at the upper edges, and the adjacent smaller annular bead c' .

The design of the body B comprises the plain parallel sides d d , corresponding with the parallel sides a a of the cover, the flat bottom e , the annular bead f at the lower edge, and the adjacent smaller annular bead f' , and the annular bead g near the upper end of the body B.

What I claim is—

The design for a wooden vial-box, substantially as shown and described.

Signed by me this 5th day of January, A. D. 1897.

WEBSTER C. ESTES.
